H. WESTERHOLD
PARTURITION INSTRUMENT
Filed March 5, 1923

UNITED STATES PATENT OFFICE.

HENRY WESTERHOLD, OF PENDER, NEBRASKA.

PARTURITION INSTRUMENT.

Application filed March 5, 1923. Serial No. 622,854.

To all whom it may concern:

Be it known that I, HENRY WESTERHOLD, a citizen of the United States, residing at Pender, in the county of Thurston and 5 State of Nebraska, have invented certain new and useful Improvements in Parturition Instruments, of which the following is a specification.

This invention relates to instruments to 10 facilitate parturition.

The primary object of this invention is the provision of an instrument constructed from a humanitarian standpoint to facilitate parturition, being particularly well 15 adapted for use on dumb animals, such as sows, sheep, and the like.

A further object of this invention is the provision of an instrument of the above 20 mentioned character, by which parturition may be facilitated, without injury to the mother or to the young, being so constructed that the same may be utilized for easy delivery independent of whether the young is 25 delivered head foremost or feet foremost.

Other objects and advantages of this 30 invention will be apparent during the course of the following detailed description.

In the accompanying drawing, forming a 35 part of this specification, and wherein similar reference characters designate corresponding parts throughout the several views.

Figure 1 is a front elevation of the improved parturition instrument.

Figure 2 is an edge elevation of the improved parturition instrument.

Figure 3 is a fragmentary cross sectional view of a portion of the parturition instrument, showing a joint thereof so constructed 40 that there will be no liability of injury whatsoever to the mother or to the young, incident to a parturition operation.

In the drawing, wherein for the purpose 45 of illustration is shown but the preferred embodiment of this invention, the letter A generally designates the improved device, which is preferably constructed of medium gauge wire, of inherent rigidity, providing a straight handle portion 9, having an elongated substantially oval shaped loop 10 bent at the forward end thereof, the arcuate sides 50 11 and 12 of which loop, for their major lengths, are in the same plane; the arcuate forward or tip portion 13 of the loop 10 being offset in a plane disposed at an obtuse

angle with respect to the plane in which the major lengths of the sides 11 and 12 lie. It is to be noted that the free end of the wire in the provision of the loop 10 is bent, as at 55 15, for a series of convolutions about the most forward end of the straight handle 9, and this joint, including the series of convolutions, is sealed by means of a substantially oval shaped lead or metal casing 16 having exteriorly smooth or convex surfaces 60 as to eliminate all sharp corners whatsoever at the juncture of the loop 10 with the handle 9.

At its opposite or rear end, the straight handle portion 9 is provided with a relatively smaller loop 20 which may be elongated or oval shaped, but the sides and ends 65 of which are in the same plane; the opening 21 provided by this loop 20 being materially smaller than the opening 22 provided by the forward or elongated loop 10. The joint 24 provided at the juncture of the loop 20 with the handle 9 is exactly identical with the joint described for juncture of the loop 10 with the handle 9, and is formed by spirally winding the free end of the loop 20, as at 25, about its adjacent handle portion 9, and sealing these convolutions by a lead casing 26 of identical construction with the casing 16.

For ordinary parturition, the large loop 10 is used, by slipping the same over the head of the young to be delivered; the same being particularly effective in this respect incident to the fact that the end or tip 13 is offset to permit the same to have a snug grip upon the nape of the young, or at the rear of the skull, so that the operator may aid parturition by simply pulling upon the instrument A or by pressing the head of the young with one hand and pulling upon the instrument A with the other. This type of instrument is more effective than the hinged forceps heretofore used, as the same is more compact and is more humanitarian, in that there are no crossing parts or abrupt junc- 75 tures to injure the mother or young, and incident to its construction takes but little space to effect an operation.

The instrument A may also be effectively used for delivering the young when parturition takes place with the feet of the young foremost. In this case, the loop 20 will be used, the same being hooked over the legs of the young to be delivered. In the main, 80 105 110

the loop 20 will serve as a hand grip in facilitating parturition which takes place with the head foremost.

It is to be particularly noted that the instrument A is so formed that the elongated loops at the ends of the intermediate handle portion 9 have elongated openings arranged so that the major axes thereof are aligned longitudinally with each other 10 and with the straight intermediate handle portion 9.

The improved instrument is primarily designed to facilitate parturition in the case of dumb animals, although the same 15 can be used in this connection with human beings.

Various changes in the shape, size and arrangement of parts may be made to the form of invention herein shown and described, without departing from the spirit of the invention or the scope of the claims. 20 I claim:

1. A parturition instrument formed of a length of wire bent to provide a handle por-

tion having at one end thereof a portion 25 looped in oval shaped manner and spirally wound at its free end about the adjacent end of said handle portion, and protecting means sealing the juncture of the loop and handle portions to provide smooth unbroken 30 surfaces, the forward end of said elongated loop being angularly bent.

2. A parturition instrument formed of a length of wire bent at one end to provide an elongated closed loop having an elongated opening therein, and at its other end bent to provide an elongated closed loop having an elongated opening therein of less length and width than the first mentioned loop, the intermediate portion of the wire between 35 said loops being of a single substantially straight strand and providing a handle, said loops being so formed that their elongated openings have the major axes thereof in longitudinal aligning relation with each other and with the intermediate portion of 40 said wire.

HENRY WESTERHOLD.
